KEY RETAINER

Garland L. Adair, Fort Worth, Tex.

Application October 29, 1945, Serial No. 625,403

5 Claims (Cl. 70—456)

1

This invention relates to key cases, and the like, in which a selection of keys may be placed and conveniently carried in the pocket; and its primary object resides in the provision of a key retainer having a plurality of compartments separated to accommodate one or more keys in each providing a novel means of securing the keys therein.

Another object of the invention resides in the provision of a compact arrangement of compartments in which a selection of several keys may be encased for ready access and providing a flexible means for collectively retaining the keys in their respective compartments which also provides for the return of a selected key to its compartment by proper manipulation of the said means.

Broadly, the invention seeks to comprehend the provision of a key case, or retainer, in which the keys have separated compartments capable of ready and easy access and affording a novel arrangement of securing the keys, while in use, to the case and returning the same to its respective place in the case when not in use.

While the foregoing objects are paramount, other and lesser objects will become manifest as the description proceeds, taken in connection with the appended drawings wherein:

Figure 1 is an elevational view of the invention illustrating the arrangement whereby each separator can be displaced for free access to the selected key.

Figure 2 is a side elevational view of the invention showing the spaced separators defining key compartments therein.

Figure 3 illustrates the manner in which a key may be returned to its compartment after use.

Figure 4 is an elevational view of a modified form of outer case for the invention.

Figure 5 is a side elevational view of the modified form of the invention in which the outer case is connected across the bottom by a spring, and

Figure 6 illustrates, in cross-section, one form of construction for the separators and the outer case in the form of the invention shown in Figures 1, 2 and 3.

The invention comprises an outer case 1 formed of a pair of elongated members 2 preferably wider at their upper ends *a* and symmetrically formed, as shown in Figure 1, and connected at their lowermost ends *b* by a pliable material 3, such as leather, or the like. The members 2 are preferably formed with wire frames 4, or the like, covered with the pliable material 3, previously mentioned, as shown in Figure 6.

The outer case 1 embraces a plurality of sepa-

rators 5 which are shaped exactly like the members 2 of the case 1 and symmetrically conform thereto, as shown in Figures 1 and 3. Each of the separators 5 has a longitudinal slot 6 therein near its lower end, as shown in dotted lines in Figure 1, through which a coupled screw 7, or the like, is arranged, as in Figure 2, which extends through both of the outer members 2.

A spacer washer 8 is arranged about the screw 7 between each of the separators 5 to provide compartments therebetween for keys 9 which are arranged upon a string 10 extending through apertures 11 in the members 2 and 5 positioned near the upper ends thereof. The string 10 is detachably secured at one end *c* to one of the members 2, as illustrated in Figure 2, by any suitable means, and has its opposite end free although knotted or provided with some device 12 for preventing its being withdrawn through the apertures 11. It is desirable that the free end of the string 10 be of sufficient length to permit any one of the keys 7 to be withdrawn from its compartment, as in Figures 2 and 3, and used without disarranging any of the other keys; the device 12 limiting its movement, as previously described.

In Figure 3 is illustrated the manner in which the invention is manipulated. A key selected for use can be removed from its compartment by slightly raising an adjacent separator 5, by reason of the slot 6 therein, and tilting the same outwardly at the top, as illustrated also in Figure 1, so that the selected key can be handled. By pulling the key out of its place the string 10 will flex out so that the key may be freely placed in a lock (not shown) while the case swings thereon, as in Figure 2. When it is desired to return the key to its place the free end of the string 10 may be grasped by one hand and pulled causing the key to be returned to its respective compartment and, at the same time the displaced separator 5 will also be aligned with its companions, as shown in Figure 3.

In the modified form of the invention, shown in Figures 4 and 5, it is desirable to provide an outer case 13 which comprises a single unit of some flexible but spring-like material, such as metal or plastic, and formed substantially U-shaped, as in Figure 5, the general form of the parallel members 14 being the same as the members 2 in the structure shown in Figures 1, 2 and 3.

It is desirable to form the case 13, therefore, by stamping the same from flat, relatively thin stock, and bending the same at *d* so that the members 14 are parallel. It is also desirable to provide laterally extending portions 15 on each side of the

structure, as illustrated in Figure 4, near the lower ends of the members 14, which are bent inwardly and at right angles to the latter to provide a kind of closure for the lower end of the case 13, as shown in Figure 5, to embrace the lower ends of the separators 16 which, in this structure, are secured to the case 13 only by the string 10 which is passed through apertures 11 in the upper ends of the members 14 and separators 16.

The arrangement of the modified structure permits the withdrawal from the assembly of both the selected key and the separator 16 adjacent thereto, if desired, although the flexibility of the case 13 will permit the members 14 to be flexed outwardly to afford access to the several compartments at will. The arrangement of the string 10, however, will enable the modified structure to be manipulated in the same manner the structure shown in Figures 1, 2 and 3 is operated, in all other respects, for replacing a key to its proper compartment after use.

It is obvious that certain changes as to structure, design and material may be resorted to from time to time, by persons skilled in the art, without departing from the spirit and intent of the invention or the scope of the appended claims.

What is claimed is:

1. In a key retainer having a plurality of compartments, a plurality of separators having their lowermost ends restricted to limited vertical movement and having their upper ends free and capable of separation, a key string arranged through apertures in the upper ends of the said separators whereby to secure a key in each compartment between each separator.
2. In a key case having a plurality of key compartments defined by an arrangement of elongated separators having their faces slightly spaced, means securing the lowermost ends of the separators providing for a limited vertical movement and oblique arrangement of the said separators to gain access to selected keys and flexible means for collectively securing the keys in the said compartments.

3. In a key retainer having a plurality of slightly spaced separators defining key compartments thereinbetween, the said separators having their lower ends joined for limited vertical and pivotal movement, means comprising a string arranged through each of the separators near their uppermost ends for retaining a key in each of the compartments, the said means providing for the removal of a selected key and the return thereof to its compartment.

4. In a key retainer having a plurality of spaced separators defining key compartments, means securing the lowermost ends of the separators providing for limited individual vertical movement thereof and sidewise displacement of their upper ends of each with respect to others thereof and means comprising a key string arranged through each separator for retaining a key in each compartment therebetween and providing means for returning the selected key to its compartment.

5. In a new article of manufacture, a key case formed with a plurality of key compartments, an arrangement of spaced separators defining the said compartments and secured at their lower ends by means providing for limited movement thereof, means for retaining a key in each compartment, the said means comprising a string arranged through each of the said separators and capable of returning the selected key to its compartment after use.
